REMOVABLE SUB-COMPARTMENT END
CLOSURE FOR RECEPTACLESIsaac L. Wilcox, Fulton, N. Y., assignor to Oswego
Falls Corporation, Fulton, N. Y., a corporation
of New York

Application September 22, 1936, Serial No. 101,983

5 Claims. (Cl. 229—15)

This invention relates to containers, or receptacles, of the type used in connection with the retail of merchandise in small quantities. These containers are usually formed of paper, or similar fibrous material, and are used in connection with the sale of ice-cream, and similar products.

The general object of my present invention is the provision of a removable sub-compartment end closure for such a container. In connection with the sale of certain products, such as ice-cream, the customer often purchases one or more other products such, for example, as syrups to be used in connection with the ice-cream, or product being purchased. My removable sub-compartment end closure provides a separate compartment, or space, for such additional product, and a further object of my invention is a sub-compartment removable end closure of particularly simple and economical construction, 20 and which can be conveniently filled, sealed and adapted to the main body of the container.

The invention consists in the novel features and in the combinations and constructions hereinafter set forth and claimed.

25 In describing this invention, reference is had to the accompanying drawing in which like characters designate corresponding parts in all the views.

Figure 1 is an elevational view showing a preferred embodiment of my detachable sub-compartment end closure applied to a container and being partly in section.

30 Figure 2 is an exploded view of the main elements comprising the end closure, illustrating the manner in which the end closure is assembled.

The invention consists generally of the combination of a conventional tubular receptacle and a detachable sub-compartment end closure, which consists of a cup shaped member with the 35 flange, or side portion, of said member complementary in cross section to the body of the container, and which is encircled by a band extending beyond one end of the cup member and frictionally engaging the open end of the receptacle. The sub-compartment is formed by a disk of thin, flexible material, such as cellophane, being arranged over the open end of the end closure after the contents has been placed therein, and with the periphery of the sheet extending 40 between the outer surface of the flange of the cup shaped end closure and the band.

A conventional type of container is illustrated in Figure 1, and comprises a tubular body portion 10, usually circular in cross section, and 45 provided with a bottom closure 11 which is se-

cured to the body 10 by the conventional crimp, as at 12, or in any other suitable manner.

The removable end closure comprises a cup shaped member formed by a discoidal portion 13, to the periphery of which is secured a band or flange member 14. These elements may also be secured together as by crimping, as at 15. The flange member 14 is complementary, in cross sectional dimension, to the tubular body 10 of the receptacle. After the receptacle is filled with 10 ice-cream, for example, the end closure is inverted, as shown in Figure 2, and the syrup, or other desired product, placed therein. Subsequently, a disk or sheet 16 of thin, flexible material, such as cellophane, is arranged over the 15 open end of the end closure, and a sleeve or band 17 is pressed axially of the end closure, by which action the peripheral portion of the sheet 16 is folded downwardly about the outer surface of the flange 14. The sleeve 17 is preferably of 20 appreciably greater length than the length of the flange 14, and extends outwardly beyond one end of the flange. The outwardly extending portion of the band 17 frictionally encircles the upper end of the body 10, whereby the end closure, after the same has been filled and assembled, may be applied to the container in the same manner as the conventional slip cover with the sheet 16 arranged inwardly, as shown in 25 Figure 1, or outwardly to provide a window 30 through which the contents of the end closure may be inspected. In the latter instance, the sleeve or band 17 would be pushed farther on the flange 14, so that the sleeve would extend beyond the opposite end of the flange.

The inner diameter of the sleeve or band 17 is such as to tightly engage the flange 14 and accordingly, the peripheral portion of the disk 16 is securely clamped between the flange 14 and the sleeve 17. I have found that if the parts of 35 the end closure are proportioned approximately, as illustrated in Figure 1, the sheet 16 is secured to the end closure in liquid tight relationship, and will not leak with thin liquids, such as water, over a period of several hours.

If preferred, the inner surface of the sleeve 17 40 may be formed or provided with inwardly extending ribs 20, 21, the ribs 20 being preferably spaced equal distances from the ends of the sleeve 17, and the rib 21 being arranged midway 45 between the ends of the sleeve. In this instance, the sleeve 17 is of slightly greater diameter than the body 10 and the flange 14. With this arrangement, the sleeve 17 may be more easily 50 pressed over the marginal portion of the disk 16, 55

- and the flange 14, and the end closure more easily applied to the end of the body 10. With this arrangement, the ribs 20 frictionally engage the body 10 to form a tight, liquid proof joint, regardless of which end of the sleeve 17 extends beyond the flange 14, and the intermediate rib 21 tightly presses the flange of the disk 16 against the outer surface of the flange 14 forming a liquid tight joint between these members.
- 5 10 15 20 25 30 35 40 45 50
- 10 Preferably, the sleeve 17 is provided with one or more small apertures 22 arranged between the rib 21 and ribs 22. The purpose of these apertures is to permit the escape of air from within the extending portion of the sleeve 17 while it is being pressed on the end of the body 10.
- 15 It will be observed that should the customer desire to purchase a quantity of syrup to be used with the ice-cream contained in the receptacle, the clerk or attendant can quickly and conveniently fill the end closure with syrup, lay the sheet 16 over the open end thereof and press the sleeve 17 over the flange 14, and when thus assembled the unit comprises an end closure for the container.
- 20 25 30 35 40 45 50
- 25 It will be understood and appreciated that there are a number of instances where it is desired to package two products, which are generally used together, in one package, and my removable sub-compartment end closure is particularly adapted for such use.

What I claim is:

1. The combination of a receptacle having a tubular body portion and a removable sub-compartment end closure for one end of said body, 35 said end closure comprising a discoidal portion having a depending annular flange complementary to said tubular body, with the edge of the flange abutting against the end of the body portion, a band encircling said flange and the end portion 40 of said body, and a disk of thin, flexible material arranged over the open end of the flange and being secured at its periphery between the outer side of said flange and the inner surface of said band.
- 45 50 2. The combination of a receptacle having a tubular body portion and a detachable sub-compartment end closure for the receptacle, said end closure comprising a cup shaped member arranged with its open end abutting against the end of the body portion, a band encircling said

cup portion and the end portion of the body, and a disk of thin, flexible material arranged across the open end of the cup member and being secured at its periphery between said cup member and said band.

5 10 15 20 25 30 35 40 45 50

3. The combination of a receptacle having a tubular body portion forming a main compartment, and a detachable end closure forming a sub-compartment, said end closure comprising a discoidal portion having a depending annular flange secured to its periphery, a sheet of thin, flexible material arranged across the open end of said flange, with the peripheral portion of said sheet overlapping the outer surface of said flange, a band encircling said flange and peripheral portion of said sheet, and having a portion extending beyond said flange and frictionally engaging the end of the body portion, and said band being provided with an aperture adjacent the open end of said flange to permit the escape of air when said end closure is applied to the end of the body.

4. The combination of a receptacle having a tubular body portion forming the main compartment of the receptacle, and a detachable end closure forming a sub-compartment, said end closure comprising a cup shaped member, a sheet of thin, flexible material arranged across the open end of the cup shaped member, with a periphery of said sheet folded about the outer side of said member, and a sleeve frictionally 30 35 40 45 50 encircling the outer side of said member and securing the periphery of said sheet between the sleeve and said member, and said sleeve extending outwardly beyond the open end of said member and arranged to frictionally encircle the open end of the body portion.

5. The combination of a receptacle having a tubular body portion and a detachable sub-compartment end closure for the receptacle, said end closure comprising a cup shaped member formed of relatively stiff fibrous material, a band encircling the periphery of said cup portion, a sheet of thin, flexible material arranged across the open end of the cup member and being secured at its periphery between said cup member and said band, and said band extending beyond one end of said cup member with the extending portion encircling the end portion of the body of the receptacle.

ISAAC L. WILCOX.
